UNITED STATES PATENT OFFICE.

LEON E. LA BOMBARD, OF CHELSEA, MASSACHUSETTS, ASSIGNOR TO SPECIALTY AUTOMATIC MACHINE COMPANY, OF CHELSEA, MASSACHUSETTS, A CORPORATION OF MASSACHUSETTS.

MACHINE FOR MAKING BOXES.

1,407,331.

Specification of Letters Patent. Patented Feb. 21, 1922.

Application filed September 16, 1916, Serial No. 120,438. Renewed August 29, 1919. Serial No. 320,693.

To all whom it may concern:

Be it known that I, LEON E. LA BOMBARD, of Chelsea, in the county of Suffolk and State of Massachusetts, have invented certain new and useful Improvements in Machines for Making Boxes, of which the following is a specification.

This invention relates to means for facilitating the folding of boxes, and refers particularly to a machine of a type which may be properly termed "semi-automatic" because a portion of the operation of folding the boxes is performed by hand.

A type of box commonly called an ice cream pail is most commonly produced entirely by hand, from a blank formed substantially as shown in Figure 7 of the accompanying drawings, the operator applying the adhesive manually.

Although I do not limit myself to the specific type of box or pail mentioned, the particular object of my invention is to provide a machine which will automatically apply adhesive to the proper portions of the blanks and deliver said blanks to position where they can be quickly folded by hand and nested, and started on their way through automatic adhesive setting mechanism so that the boxes will issue from the machine nested and with the adhesive fully set.

With such objects as described in view, my invention consists in the improvements which I shall now proceed to describe and claim.

Of the accompanying drawings:

Figures 1 and 2, on two sheets, when taken together represent a side elevation, partly in section or broken out, of a complete machine embodying my improvements.

Figure 3 represents a plan view of the parts shown in Figure 2.

Figure 4 represents a plan view of the parts shown below the line 4-4 of Figure 1.

Figures 5 and 6 represent a section on line 5-6 of Figure 3, on a larger scale.

Figure 7 is a plan view of a blank for forming what is known as an ice cream pail.

Similar reference characters indicate the same or similar parts in all of the views.

The bars 12 indicated in Figures 1 and 2 represent portions of a suitable framework for the entire machine. Of course, any suit-

able framework may be employed. The bars 12 are supported by suitable legs 13.

An endless, slowly travelling carrier belt 14 passes around a pulley 15, (Figs. 2 and 3) and around a large pulley 16 (Fig. 1), said pulley being carried by a shaft 17, said shaft having also a gear 18 meshing with a pinion 19 carried by a shaft 20 (see also Fig. 4). The shaft 20 has a pulley 21 and is driven by means of a belt 22 from a pulley 23 on a shaft 24 which is driven as hereinafter described. A suitable tightener for the carrier belt 14 is indicated at 25.

A belt 26 is mounted upon pulleys 27, 28, 29 and 30, the portion of said belt which is closely adjacent to the belt 14 serving to reverse the blanks, or turn them upside down. As hereinafter described, the blanks, having adhesive applied to portions of their under surfaces are deposited on the belt 26 near the pulley 30, with the coated portions of the blanks projecting beyond the edges of the belt 26 so that no adhesive will be transferred to said belt. The blanks then are grasped between the belts 14 and 26, which are travelling in the direction of the arrows in Figure 1, and are carried around until they are released from that portion of the belt 26 which is mounted on the pulley 27, the blanks then travelling along the upper surface of the upper stretch of the belt 14 in a direction toward the left in Figure 1 toward the folding or manipulating table presently described. The upper stretch of the belt 14 is supported by a suitable strip 31.

As shown in Figure 2 the belt 14 extends down below the plane of the main portion of its travel, and below the plane of the table 32, so that, as the belt 14 travels around the pulley 15, the blanks simply slide off onto the table 32 if they have not previously been taken up by the operator. In Figure 3 the dotted lines indicate the relative size of one of the blanks as it is leaving the belt 14, if the blank has not been folded prior to its reaching that point. In other words, the blanks are wider than the belt and the opening through which the belt passes toward the pulley 15, so that no blank can pass down through said opening. In practice, however, as will be explained, the operator does most, if not all, of the manipulating of the blanks which fold them up to pail form while

travelling along on the slowly moving belt 14, slipping each pail-shaped article into the preceding pail-shaped article so that said articles in nested form will travel along between the belts 34 presently described.

The table 32 has an extension or tongue 33 (Figs. 2 and 3) which extends partially into the space between two presser belts 34, the acting stretches of which are parallel or substantially so and constitute travelling vertical walls which grasp, and press with sufficient force to set the adhesive, the nested boxes that are being pushed along by and between said belts 34. Each belt 34 is mounted upon pulleys 35 and 37 carried by the ends of suitable supporting bars 36. Each pulley 37 is carried by a vertical shaft 38 mounted in a suitable bearing and having a worm wheel 39 driven by a worm 40 carried by a shaft 41, said shaft 41 carrying the two worms for actuating the two worm wheels and the two presser belts. The shaft 41 has a pulley 42 on which is mounted a belt 43 driven by a pulley 65 (Fig. 4) carried by shaft 64 hereinafter described.

In order that the stretches of the belts which form the walls for the nested series of boxes may exert a yielding pressure upon said nested boxes, I provide a series of rolls 46 (Figs. 2, 3, 5 and 6) mounted upon stud shafts 47 rising from brackets 48 which are pivotally connected to the bars 36 at 49. The brackets have lugs 50 which straddle the bars 36, and springs 51 inserted between one lug of each bracket, and the bar 36, as shown in Figures 5 and 6, exert a constant tendency to force the rolls 46 of the two series of rolls toward each other, to the limit prescribed by the other or outer lugs 40 of the brackets.

The bars 36 are supported by any suitable frame work such as cross rods 52, having legs 53, and suitable tightener rolls 54 (Fig. 3) are provided for the belts 34.

I will now describe the mechanism for applying the adhesive to the proper portions of the blanks *a*, shown in Figure 7, the areas which receive the adhesive being shaded.

Referring to Figures 1 and 4, a suitable glue receptacle 55 is provided, two glue wheels 56 being carried by a shaft 57 which is rotated by suitable gearing not necessary to describe. A chain 58 having spaced lugs 59 is mounted at one end upon a sprocket 60 carried by a shaft 61, and at the other end by a sprocket 44 carried by a shaft 45.

As this chain is mounted so that it runs between the two wheels 56, the glue receptacle 55 will also be preferably made as two receptacles or boxes instead of one, with a space between two such receptacles for the passage of the lower stretch of the chain 58.

A suitably supported inclined table or

chute 62 is provided for the blanks, a timed feed wheel 63 of a well known type taking said blanks singly from the table or chute and feeding them onto the chain 58. The feed wheel 63 is carried by a shaft 64 which shaft also carries the pulley 65 for the belt 43 as hereinbefore described. The shaft 64 is driven by a chain 66 which in turn is driven by the shaft 24. The shaft 24 is driven through the medium of suitable gearing 67 by a shaft 68 having a drive pulley 69.

As each blank is fed by the wheel 63 its edges pass under the guides 70 while its midwidth is held down by a top guide 71 supported by a cross rod 72.

The friction of the bars is such that when each blank arrives at this point, it stops until one of the lugs of chain 58 contacts with the rear edge of the blank so as to push said blank along, the side flaps of the blank projecting and passing under segmental flap depressers or deflectors 73 which are carried by the shaft 24. The feed wheel and the feed chain and its lugs are so timed relatively to the speed of rotation of shaft 24, that the segments 73 do not act to depress the wings *a'* of each blank (Fig. 7) but only act to depress the wings *a*. The upper portions of the two glue wheels 56 are slightly below the plane of normal travel of the wings of the blanks, so that no portions of the blanks will come in contact with the glue wheels excepting those portions which are depressed or deflected by the segments 73.

To ensure continued movement of the blanks with the feed chains, I provide a series of rolls 76 carried by a bar 75 which is supported by a transverse rod 74. The bar 75 is slotted as at 77 and the rolls 76, which are duplex, have their stems mounted in the slots 77. This enables the rolls 76 to rise and fall relatively to the bar 75, said rolls simply acting as rotating weights to hold the blanks down so that the lugs of the chain cannot slip under the blanks, but will feed them along, and discharge them upon the belt 26.

It is quite essential that the blanks shall not be deposited upon the belt 26 with glued areas overlapping unglued areas. Owing to the lugs of the chains 58, the blanks leave said chain accurately timed. I provide an inclined deflector 78 supported by a suitable cross bar 79 so that the blanks are guided down onto the belt 26 with the front and rear edges of adjacent blanks so positioned relatively to each other that there will be no overlapping of portions of the blanks which carry glue. At the bottom of the deflector is a roll 80 to press the blanks on the belt 26 and keep them from twisting or falling off from said belt.

In operation the blanks *a* are automatically fed, by means of the wheel 63 and the feed chains, so that certain areas thereof, as those

indicated at α^2 in Figure 7, receive adhesive on their under surfaces and said blanks are deposited on the belt 26 in accurately spaced relationship and are then grasped between 5 the two belts 14, 26 and carried around until they escape from the belt 26 under the pulley 27 so that they move along with the somewhat slowly travelling belt 14. The operator, standing or sitting near the delivery end of the belt 14, manipulates the blanks on the creased lines to convert them to pail form. When the first blank is folded it is slid along the tongue 33 until it is 10 grasped between the very slowly travelling belts 34. Each succeeding blank is folded over, and allowed to slide along with, the preceding folded article. The folded articles are rapidly accumulated between the pressing belts 34 and it frequently happens in 15 practice that the succession of folded articles accumulates along the tongue and over the table 32 onto a portion of the belt 14.

By actual comparison tests it has been found that with a machine of this character, 20 which automatically applies the adhesive to the proper portions of the blanks, brings them to an exposed position for manually folding and then effects the setting of the adhesive and delivers the articles, produces 25 the work about four times as fast as the operator could effect the results when the glue is applied manually. And of course it will be readily understood that the glue is applied in definitely limited localities and 30 that with such machine as herein described, there is no such liability of improper application of glue as exists when the glue is applied manually.

It will be readily understood, of course, 35 that the parts of the machine may be made adjustable laterally by any suitable mechanism to provide for operating on blanks of different sizes.

It is to be understood that the terms 40 "adhesive" and "glue" used herein are synonymous. In the appended claims I employ the latter term for the sake of brevity and not for limitation.

In practice, the carrier belt 14 and the 45 cooperating turning-over belt 26, travel so slowly that the blanks delivered thereto by the glue-applying mechanism are carried along either closely adjacent or in partially overlapped relationship. Of course, however, no glue-bearing surfaces of the blanks 50 are overlapped. The blanks travel such a distance before reaching the position where they are manually folded that the glue has time to partially dry. Therefore I am able 55 to employ glue of a much more fluid nature than is employed when the folding is done immediately after the glue is applied, because a thick or quick-drying glue must be used in the last mentioned case. A com- 60 paratively thin and slow-drying glue can

be more accurately applied to the blanks, and enables the machine to run better and with less interruptions for cleaning, when the glue is thin and slow-drying.

Furthermore by this method, I am able 70 to employ glue of lower cost than a thick or quick-drying glue.

By means of the gearing described, the blanks travel rapidly up to the time when they are taken by the slowly moving belts 75 26, 14. This is due, in the machine illustrated, to the fact that the gear 18 of shaft 17 (Fig. 1) is driven by the small pinion 19 of shaft 20, said shaft being driven by belt 22 from pulley 23 of shaft 24. Each 80 revolution of shaft 24 causes the flat de-pressers 73 thereof to effect the application of glue to one blank. If the blanks were to travel at the same speed when reaching their exposed positions for folding, as they 85 do while receiving their glue, the production of the boxes would be very slow if the glue is to partially "set" as described. I am able however to effect rapid production, because the blanks are first glued singly, while 90 entirely separate from each other, are then accumulated on belt 26 in partially overlapped positions and immediately travel at reduced speed so that the glue can begin to "set," and are then inverted and travel along 95 slowly in exposed position so that they can be successively picked up for folding without having this operation on any blank interfered with by the next following blank.

The turning over is essential when the 100 blanks are overlapped, because otherwise each first blank would be partly covered by the one behind it. By turning the blanks over, each first blank is entirely free for folding because the front portion of the 105 next one is then below instead of above said first one.

Having now described my invention, I claim:

1. A machine for facilitating the production of folded boxes, comprising means for causing blanks to travel singly and separated at one rate of speed, means for applying glue to selected portions of the blanks while so travelling, and means for continuing the movement of the blanks at a lesser speed of travel in exposed positions to enable said blanks to be manually folded.

2. A machine for facilitating the production of folded boxes, comprising means for causing blanks to travel singly and separated at one rate of speed, means for applying glue to selected portions of the blanks while so travelling, and means for turning the blanks over and causing them to continue their travelling movement at a reduced speed in exposed positions.

3. A machine of the character described, having a surface for the manual folding of blanks, means for automatically applying

glue to selected lateral portions of the blanks, and means for delivering the blanks from the glue-applying means and overlapping them on said surface.

5. 4. A machine of the character described, having a surface for the manual folding of blanks, means for automatically applying glue to selected lateral under surfaces of the blanks, means for overlapping said blanks, 10 and means for turning the blanks over and delivering them to said surface.

5. A machine of the character described, comprising an endless belt having its upper stretch extending to exposed position to 15 enable blanks to be folded thereon, means for applying glue to selected lateral under surfaces of the blanks, and means for overlapping the blanks and delivering them to said upper stretch.

20. 6. A machine of the character described, comprising an endless belt having its upper stretch extending to exposed position to enable blanks to be folded thereon, a second belt cooperating with the first mentioned 25 belt for turning blanks over and delivering them to said upper stretch, said second belt having an exposed blank-receiving portion, means for applying glue to under surface portions of blanks, and means for overlapping the blanks and delivering them upon 30 said receiving portion of the second belt.

7. A machine of the character described, comprising an endless belt having its upper stretch extending to exposed position to 35 enable blanks to be folded thereon, a second belt cooperating with the first mentioned belt for turning blanks over and delivering them to said upper stretch, said second belt having an exposed blank-receiving portion, means 40 for applying glue to under surface portions of blanks and delivering them in overlapped positions upon said receiving portions of the second belt, and a deflector for guiding the blanks from the gluing means onto the exposed portion of said second belt in accurate 45 relationship.

8. In a machine of the character described, means for applying glue to selected lateral under areas of blanks, an elongated carrier 50 to expose to the atmosphere the blanks received from the gluing means and to deliver them to position for manual folding, and means for delivering the blanks from the glue-applying means to said carrier in overlapped positions.

55. 9. In a machine of the character described,

intermittently operative means for applying glue to selected marginal portions of blanks, edge guides for the blanks, and an endless carrier belt for receiving the blanks from the 60 gluing means said belt being of less width than said guides whereby the marginal portions of the blanks will project beyond the edges of the belt.

10. In a machine of the character described, 65 a pair of glue wheels in axial alignment but spaced from each other, means for causing blanks to travel in a plane spaced from the peripheries of said wheels, deflectors for acting upon portions of the blanks 70 and causing those portions to ride in contact with the peripheries of said wheels, and means for ensuring accurate spacing of the travelling blanks to cause the deflectors to act only upon predetermined portions of the 75 blanks.

11. In a machine of the character described, 80 a pair of glue wheels in axial alignment but spaced from each other, means for causing blanks to travel in a plane spaced from the peripheries of said wheels, a pair of rotary segments for acting upon portions of the blanks and causing those portions to ride in contact with the peripheries of said 85 wheels, and means for ensuring accurate spacing of the travelling blanks to cause the segments to act only upon predetermined portions of the blanks.

12. In a machine of the character specified, 90 means for holding folded blanks under continued pressure, said means comprising a pair of substantially parallel bars, brackets pivotally supported on said bars and having lugs straddling said bars and stud shafts rising from said brackets, rolls mounted on the stud shafts, springs for swinging the brackets and their rolls of the two bars toward each other, a pair of belts having their operative stretches yieldingly backed by said 95 rolls, and means for driving said belts.

13. A machine of the character described, 100 having an elongated exposed surface for manual folding of boxes thereon, said surface being supported to resist folding pressure thereon, means for applying glue to 105 blanks, means for delivering the blanks from the glue-applying means to said exposed surface, and means for exerting pressure on the folded blanks.

In testimony whereof I have affixed my 110 signature.

LEON E. LA BOMBARD.
